BOTTLE STOPPER AND POURER

Saverio A. Renzi, Jersey City, N. J.

Application June 20, 1950, Serial No. 169,107

7 Claims. (Cl. 222—479)

1

This invention relates to new and useful improvements in dispensing attachments for liquid containers, as liquor bottles, and, more particularly, the aim is to provide a novel and valuable unit of the kind comprising a stopper for such a bottle, a pouring spout forming part of a structure sleeved by said stopper with the latter of cork or the like and of tubular or annular form, and a vent tube also forming part of said structure.

The principal object of the invention is to minimize the cost of manufacture of a device as above, yet to produce the same in an assembly of the component parts such that important improvements are attained in regard to ruggedness and durability of construction as well as in regard to dependability of operation.

As the invention is preferably carried out, for attainment of the above and other objects, the spout, as the main structure of the unit, is rolled up from a single sheet metal blank; also, while the spout is thus being rolled up (and, because of the shape of the blank, so as to establish a spout which gradually decreases in cross-sectional area along a portion of its length and toward what is to be its pouring end), the blank is die worked not only preferably to longitudinally arch the spout along said portion of its length but also to provide special formations at spaced points along the spout for use in facilitating proper and secure attachment of the vent tube to the spout as said main structure.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a unit constituting one now favored embodiment of the invention.

Fig. 2 is a similar view, showing said unit with the tubular cork removed.

Fig. 3 shows said cork in axial section.

Fig. 4 is, in full lines, a bottom plan view of the parts of Fig. 2.

Fig. 5 is an enlarged longitudinal section taken on the line 5—5 of Fig. 2, with the vent tube shown fragmentarily and partially in side elevation.

Fig. 6 is a transverse section taken on line 6—6 of Fig. 5.

Fig. 7, drawn to the same scale as Fig. 5, is a

longitudinal central vertical section illustrating a modification, with here, also, the vent tube shown partially in side elevation.

Fig. 8 is an end elevation, looking toward the left in Fig. 7.

Fig. 9 is, on still a further enlarged scale, a transverse section taken on the line 9—9 of Fig. 7.

Referring now to the drawings more in detail, and first to Figs. 1 to 6, the unit as here illustrated is shown as incorporating as its main structure a pouring spout 15, and as also including a vent tube 16, an annular flange 17, and a tubular cork 18.

The spout 15, as herein shown, is one rolled up from a thin sheet metal blank which was of the outline of a truncated triangle considerably attenuated in the direction of its altitude, thereby to provide a spout of the relative length illustrated as compared with its larger and smaller diameters at opposite ends.

In thus forming the spout 15, it was also so die worked or otherwise equivalently worked as to become suitably longitudinally arched, between the revised point of attachment of the flange 17 and the end of the spout of smaller diameter, that is, the end thereof which is to be its pouring end. The meeting edges of said blank, when the spout is thus finally formed, lie along a line 19, while one of said edges is seen at 19a in Fig. 5. Preferably, said blank is so precisely cut, and the die working thereof is so properly done, that a leak tight joinder of said edges is attained along the line 19, from one end of the spout 15 to the other, without the necessity of depending on soldering, brazing or the like.

The annular flange 17, of cupped cross-section as shown best in Fig. 5, is firmly attached to the spout 15, at the location along the spout appointed for placement of said flange, in any suitable way, as by brazing, soldering or the like.

Said flange 17 is desirably so located on the spout 15 that, when the cork 18 is placed on the spout as shown in Fig. 1, and so as then to have the end of the cork of greater diameter set squarely in the cup provided by said flange, the end of the cork of lesser diameter will project somewhat beyond the end of the spout of larger diameter, as indicated in dot and dash in Fig. 4.

As will be understood, it is the last-mentioned end of the cork which, when the pouring-spout unit is to be attached to a bottle, is first entered into the latter at its neck opening, preparatory to forcing the cork down tight into said neck, thereby to extend well down into the bottle the

portion of the vent tube 16 projected beyond said end of the cork of lesser diameter.

The special formations on the spout 15 already referred to as employed for facilitating proper and secure attachment of the vent tube 16 to the spout, are two in number, as will appear hereinafter. These formations may be established, each in whole or in part, during the making of the blank of which the spout is to be formed, and/or during the forming of the spout from said blank, and/or subsequently to the making of the spout except for one or both of said formations; in accordance with methods well understood in the sheet metal working art.

The air inlet end of said tube 16 is designated 16^a, and this end of the tube is slightly upwardly canted as shown best in Fig. 5. Said end of the tube 16 extends into a recess at the exterior of the spout 15 established by an inward dimpling of the latter as at 20; ingress into said recess for the vent tube 16 being afforded by an aperture through the wall of the spout at said dimpling, as indicated at 21. This aperture 21 is of such shape and size that, when said end 16^a of the tube 16 is forced therethrough to locate said tube end 16^a in said recess, the tube 16 will be girthingly gripped tightly and in a leak-proof manner where it passes through said aperture, by the metal material of the spout 15.

Said dimpling 20 and said aperture 21 together constitute one of the two formations on the spout 15 previously referred to as employed for facilitating proper and secure attachment of the vent tube 16 to the spout.

The other of said two formations on the spout 15 is a strip-like portion of the metal thereof, at the end of the spout of greater diameter, and bounded along one side by a cut through the spout metal as indicated at 22; with said strip-like portion forced down into the spout to establish a cradling strap 23 for the vent tube 16 well removed from the dimpling 20 and also well removed from the end of said tube opposite to its end 16^a. As perhaps best indicated in Fig. 6, the strap 23 is so formed that it, and the spout metal alongside the cut 22, combine to provide a means integral with the spout for tightly gripping the vent tube 16, and consequently, in combination with the elements 20 and 21, for holding the vent tube against longitudinal movement relative to the spout and also against any shifting of said tube laterally thereof.

Soldering, brazing or the like may be utilized at one or both of said two formations; but this may be dispensed with, to avoid the slight extra cost entailed, as not absolutely necessary.

Referring to the modification of Figs. 7, 8 and 9, here the parts to which are applied reference numerals with primes added correspond, respectively, to the parts to which have been applied the same reference numerals without primes. In this construction, however, the spout 15' is so formed that, starting at a point at about where the dimpling 20 would be placed, the spout has a groove extended along its length; such groove, designated 24, extending all the way to the smaller or pouring end of the spout.

It will be noted that the end of said groove 24 adjacent to the flange 17' is shaped as is the end of the dimpling 20 adjacent to the flange 17; and that the aperture 21' is placed at the last-named end of the groove 24 in accordance with the placement of the aperture 21 relative to the dimpling 20.

The vent tube 16', engaged by the strap 23'

and by the aperture 21' in the same way as already described in connection with the engagement of the tube 16 by the strap 23 and the aperture 21, is of greater length than the tube 16. That is to say, the tube 16', instead of having an upcanted end like the end 16^a of the tube 16, is longitudinally prolonged beyond the aperture 21', as at 16^b, to an extent equal to the length of the groove 24. This prolongation 16^b of the vent tube is, furthermore, longitudinally arched for accommodation in, and for preferably tight fitting relation to, the groove 24.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A dispensing attachment for liquid containers, comprising a pouring spout constituting the main structure of the attachment, a tubular cork sleeving said spout along an end portion thereof and at the end thereof remote from the pouring end thereof, an air vent tube extending over a portion of its length into and along the length of the pouring spout, and means integral with the pouring spout for girthingly engaging the said vent tube and holding the same in fixed position relative to the pouring spout, said means comprising formations on the pouring spout one of which includes an aperture through the wall of said spout, said spout being longitudinally arched along a portion of its length and in a direction toward its pouring end, said aperture being adjacent to the end of said spout remote from its pouring end, another of said formations on the spout being a strap element bent inwardly and elongate in a direction extending circumferentially of the spout.

2. A dispensing attachment for liquid containers, comprising a pouring spout constituting the main structure of the attachment, a tubular cork sleeving said spout along an end portion thereof and at the end thereof remote from the pouring end thereof, an air vent tube extending over a portion of its length into and along the length of the pouring spout, and means integral with the pouring spout for girthingly engaging the said vent tube and holding the same in fixed position relative to the pouring spout, said means comprising formations on the pouring spout one of which includes an aperture through the wall of said spout, said spout being longitudinally arched along a portion of its length and in a direction toward its pouring end, said aperture being adjacent to the end of said spout remote from its pouring end, another of said formations on the spout being a strap element elongate in a direction extending circumferentially of the spout, said strap element being bent inwardly to extend about said vent tube on the side facing toward the center of said spout.

3. A dispensing attachment for liquid containers, comprising a pouring spout constituting the main structure of the attachment, a tubular cork sleeving said spout along an end portion thereof and at the end thereof remote from the pouring end thereof, an air vent tube extending over a portion of its length into and along the length of the pouring spout, and means integral with the pouring spout for girthingly engaging

the said vent tube and holding the same in fixed position relative to the pouring spout, and said means comprising formations on the pouring spout one of which includes an aperture through the wall of said spout, said spout being longitudinally arched along a portion of its length and in a direction toward its pouring end, and said aperture being adjacent to the end of said arching remote from the pouring end of the spout, another of said formations on the spout being a strap element elongate in a direction extending circumferentially of the spout, said strap element being bounded along one side by a cut through the spout wall made in a direction extending circumferentially of the spout, said strap element being displaced in toward the center line of the spout and as thus displaced being longitudinally curvilinearly extended, said strap element along its opposite side being bounded by a portion of the peripherally extending edge of the spout at its end remote from its pouring end.

4. A dispensing attachment for liquid containers, comprising a pouring spout constituting the main structure of the attachment, a tubular cork sleeving said spout along an end portion thereof and at the end thereof remote from the pouring end thereof, and air vent tube extending over a portion of its length into and along the length of the pouring spout, and means integral with the pouring spout for girthily engaging the said vent tube and holding the same in fixed position relative to the pouring spout, and said means comprising formations on the pouring spout one of which includes an aperture through the wall of said spout, said spout being longitudinally arched along a portion of its length and in a direction toward its pouring end, and said aperture being adjacent to the end of said arching remote from the pouring end of the spout, another of said formations on the spout being a strap element elongate in a direction extending circumferentially of the spout, said formation which includes said aperture also including an exterior recess on the spout at an inward dimpling thereof, said aperture opening into said recess.

5. A dispensing attachment for liquid containers, comprising a pouring spout constituting the main structure of the attachment, a tubular cork sleeving said spout along an end portion thereof and at the end thereof remote from the pouring end thereof, an air vent tube extending over a portion of its length into and along the length of the pouring spout, and means integral with the pouring spout for girthily engaging the said vent tube and holding the same in fixed position relative to the pouring spout, and said means comprising formations on the pouring spout one of which includes an aperture through the wall of said spout, said spout being longitudinally arched along a portion of its length and in a direction toward its pouring end, and said aperture being adjacent to the end of said arching remote from the pouring end of the spout.

the spout, another of said formations on the spout being a strap element elongate in a direction extending circumferentially of the spout, said formation which includes said aperture also including an exterior recess on the spout at an inward dimpling thereof, said aperture opening into said recess, the end of the vent tube remote from its air intake end being canted and extended beyond said aperture into said recess.

5 6. A dispensing attachment for liquid containers, comprising a pouring spout constituting the main structure of the attachment, a tubular cork sleeving said spout along an end portion thereof and at the end thereof remote from the pouring end thereof, an air vent tube extending over a portion of its length into and along the length of the pouring spout, and means integral with the pouring spout for girthily engaging the said vent tube and holding the same in fixed position relative to the pouring spout, and said means comprising formations on the pouring spout one of which includes an aperture through the wall of said spout, said spout being longitudinally arched along a portion of its length and in a direction toward its pouring end, and said aperture being adjacent to the end of said arching remote from the pouring end of the spout, another of said formations on the spout being a strap element elongate in a direction extending circumferentially of the spout, said formation which includes said aperture also including an elongate groove-like longitudinally arched recess at the exterior of the spout and extending along the length thereof toward its pouring end, said aperture opening into such groove near the end thereof remote from the pouring end of the spout, and the vent tube having a portion longitudinally curved in agreement with said arching of said groove.

40 7. In a pouring spout of elongated tubular formation and including a container engaging means, an aperture through the wall of said spout, a strap element bent inwardly and extending circumferentially of the spout together with the adjacent wall of the said spout form an inlet opening and spaced from said aperture, and a vent tube held between the wall of the spout and the inwardly bent strap element, said spout extending through said inlet opening and aperture whereby said vent tube is tightly gripped in said spout against lateral shift.
